DESIGN FOR A SOUND TRANSLATING DEVICE

Gabriel M. Giannini, Great Neck, N. Y., assignor,
by mesne assignments, to Associated Electric
Laboratories, Inc., Chicago, Ill., a corporation
of Delaware

Application February 6, 1939, Serial No. 82,795

Term of patent 14 years

To all whom it may concern:

Be it known that I, Gabriel M. Giannini, a citizen of the United States of America, residing at Great Neck, Long Island, county of Nassau, New York, have invented a new, original, and ornamental Design for a Sound Translating Device, of which the following is a specification, reference being had to the accompanying drawing, forming a part thereof.

Fig. 1 is a front perspective view, and Fig. 2

is a top plan view of the base portion of a sound translating device, showing my new design. The opposite side of my device is like the side shown.

The characteristic features of my design reside in the portions shown in solid black lines in the drawing.

I claim:

The ornamental design for a sound translating device, as shown and described.

GABRIEL M. GIANNINI.
